UNITED STATES PATENT OFFICE.

DARIUS PATTERSON, OF RICHLAND, INDIANA.

COMBINED HAME-HITCH AND COLLAR-FENDER.

SPECIFICATION forming part of Letters Patent No. 374,622, dated December 13, 1887.

Application filed June 26, 1886. Serial No. 206,381. (No model.)

To all whom it may concern:

Be it known that I, DARIUS PATTERSON, a citizen of the United States, residing in Richland township, in the county of Rush and State of Indiana, and whose post-office address is Clarksburg, Decatur county, Indiana, have invented a new and useful Combined Hame-Hitch and Collar-Fender, of which the following is a specification.

10 My invention relates to an improvement in the manner of attaching the trace or tug of a horse's harness to the hame; and the objects of it are, first, to provide a means of attaching the trace to the hame by which the trace 15 can be fastened higher or lower, as may be desired, thereby adjusting the load to the horse's shoulder, and, second, to provide a protection for the collar, thereby preventing the wearing of the collar at the place of contact 20 between it and the trace. I attain these objects by the mechanism illustrated in the accompanying drawings, in which—

Figure 1 represents the device entire. Fig. 2 shows the pin. Fig. 3 shows the adjustable 25 hitch. Fig. 4 shows the hame-butt, the cylinders, and the collar-protector.

In Fig. 1, E is a cylinder, through which passes the staple which fastens the mechanism to the hame. D is a metallic plate, which lies 30 against the face of the hame. A is the collar-fender consisting of a metallic plate lying against the face of the collar at the point of contact between the collar and the trace. B is the adjustable hitch consisting of a plate of 35 metal having a number of notches (usually seven) in its inner edge, which are intended

to receive the end link of the trace. C is a pin passing through the cylindrical ends G G of the plate B and through the cylinder F, and holds the two parts together. By removing 40 the pin C the plate B can be detached and the end of the trace can be inserted in any desired notch, and the load can be thus easily adjusted to the shoulder of any horse.

It is intended that the parts shown in Fig. 45 4 be made of one piece of malleable iron, which is formed into cylinders at E and F, with a plate of extra thickness and a plate, A, projecting beyond the cylinder F and forming the collar-fender A. The parts B and C are also 50 made of malleable iron and may be of any desired size.

What I claim as my invention, and desire to secure by Letters Patent, is—

1. The combination of the metallic collar-fender A and the adjustable hame-hitch B, and means, as shown, for uniting the one to the other, substantially as set forth.

2. The combination of the adjustable hame-hitch B, having notches cut in its inner edge 60 for receiving the end of the trace, the collar-protector A, and the pin C, substantially as set forth.

3. The metallic hame-butt and collar-fender consisting of the tubes E and F, butt D, and 65 fender A, in combination with the pin C and the hame-hitch B, all substantially as set forth.

DARIUS PATTERSON.
